BEER DISPENSING AND CARBONATING APPARATUS

Jesse F. Thomas and Claud R. Brown,
New London, Wis.

Application July 27, 1933, Serial No. 682,488

3 Claims. (Cl. 225—3)

This invention relates to a dispensing rod for beer capable of attachment to or by any standard fitting and aims to provide means whereby carbon dioxide gas may be discharged at the lower end thereof below the level of the beer in a barrel, in order to regenerate the same and render it more palatable, since the gas on rising will necessarily be absorbed to a certain extent by the beer.

10 The more specific objects and advantages will become apparent from a consideration of the description following taken in connection with accompanying drawings illustrating an operative embodiment.

15 In said drawings:—

Figure 1 is a view showing the improved dispensing rod in elevation in connection with a keg suggested in dotted lines;

Figure 2 is a view of the rod, partly broken away to disclose parts in central longitudinal section;

Figure 3 is a longitudinal sectional view taken on the line 3—3 of Figure 2;

Figure 4 is a cross sectional view taken on the line 4—4 of Figure 2;

Figure 5 is a cross sectional view taken on the line 5—5 of Figure 2;

Figure 6 is a view in elevation, and partly in central longitudinal section through a modified form;

Figure 7 is a fragmentary longitudinal sectional view of the lower end portion of the rod;

Figure 8 is a cross sectional view taken on the line 8—8 of Figure 7, and

Figure 9 is a cross sectional view taken on the line 9—9 of Figure 7.

Referring specifically to the drawings, and first to the form of Figures 1 to 5, 10 designates an attaching device whereby the implement is removably and in an air tight manner connected in the tap hole of a beer keg as suggested at 11. Said device 10 may be any standard or other tapping fixture having a nipple 10', which in the standard fixture is equipped with a threaded connection for the supply of carbonic acid gas to the top of the keg. According to our invention, an outlet rod or pipe is shown at 12 removably fastened in the fitting, with a space 12' between the fitting and pipe 12, such space being closed at the top but open at the base of fixture 10. Said outlet rod or pipe for the beer is thus in the nature of an attachment for a fitting such as 10 and capable of being sold separate therefrom. 13 are inlet openings. At the upper end of the pipe 12, a fitting 14 is connected having

an outlet or discharge passage 15 for the beer which is controlled by a faucet or cut-off valve 16.

A plug 17 is telescopically fitted in the lower end of the pipe 12 and screw-threaded thereto at 18 is a pipe 19 leading to a chamber 20 within the fitting 14 and held in place by a nut 21 disposed in said chamber and abutting a gasket 21' interposed between the same and the fitting. A conventional tap 22 including a normally closed check valve therein is screwthreaded at 23 in the wall of the chamber 20, a gasket being used at 22'. Through the tap 23 carbonic acid gas is supplied opening the check valve and entering the chamber 20 and then passing through the pipe 19 and is discharging through the lower end of the device, since the pipe 19 communicates with a bore 24 in the plug 17 from which registering ports 25 and 26 lead, being respectively provided through the plug 17 and pipe 12. It will be noted that the plug 17 is cut away to 20 provide a passage at 27, registering with the ports 13, and from which passages 27 one or more passages 28 pass to the interior of the pipe 12.

In lieu of the usual carbonic acid gas supply fitting at nipple 10', we replace the same with 25 a removable screw-threaded connection 29 which is optionally equipped with a pressure gauge 29a to enable the operator to determine when to turn on the gas supply. Connection 29 also may or may not have an automatically opening relief valve 29b to relieve against pressure above a predetermined amount, and also may have a gas connection 29c, equipped with a normally closed check valve 29d enabling carbonic acid gas to be supplied, if desired, to augment the supply 30 through fitting 22. Instead of using connection 29, nipple 10' may be plugged or closed in any desired way.

35 A clean out plug 30 is screw-threaded to the fitting 14 against a gasket 30'.

40 A modified form of the invention is shown in Figures 6 to 9. This form embodies an attaching plug 10a similar to that at 10 in which a tube 31 is removably fastened and at the top of which a fitting 32, substantially similar to that at 14 is secured. Concentric with the pipe or tube 31 is a pipe or tube 33 through which the beer is adapted to be dispensed, passing into a chamber 34 within the fitting and out of the same through an opening or passage 35 controlled by a valve 36, the tube 33 being secured in the fitting 32 by a nut 37 thereon. Chamber 34 is closed by a clean out plug 38. Said pipe 33 at its lower end is screw-threaded as at 39 to a thimble 40 having inlet ports 41 for the inlet of beer.

Carbonic acid gas from any suitable source is supplied to a chamber 42 of the fitting through a nipple 43, similar to that at 22, it being screw-threaded in place as at 44 and equipped with a 5 normally closed check valve, not shown. The gas passes downwardly in the spaces 45 between the pipes 31 and 33. Such spaces are closed at their lower ends by a reduced portion 46 on the thimble 40 extending into the same and all of 10 them at their lower ends communicate with an endless groove 47 extending around said reduced portion 46. The passages 45 lead to outlet orifices or ports 48 and thus the gas supplied thereto reaches the beer at the bottom of the keg, so as 15 to rise in the beer and carbonate the same. This form of the invention utilizes an open relief valve at 49 like that at 29.

Various changes may be resorted to, provided they fall within the spirit and scope of the in- 20 vention.

What is claimed is:—

1. A device of the class described comprising a single fitting, said fitting having an inlet passage and an outlet passage, a pipe extending from one 25 of said passages through the other passage, fastening means on the pipe preventing downward displacement from the fitting, and cutting off direct communication between the passages, a pipe about the first mentioned pipe in communication 30 with the other passage, means supported by the first mentioned pipe at its lower end in supporting contact with the second mentioned pipe and ports through one of said pipes and said means for discharge and intake purposes.
- 35 2. A device of the class described comprising a single fitting, pipes depending therefrom and spaced one within the other, the innermost pipe being a discharge pipe, fastening means at the

upper end of the inner pipe preventing removal thereof downwardly from the fitting, the outermost pipe terminating below the upper end of the innermost pipe and providing passages between the same and the other pipe for the inlet of gas, a thimble extending into and supporting the outermost pipe at the lower end and into which the innermost pipe is screw-threaded, and said thimble having inlet passages communicating with the interior of the innermost pipe, the outermost pipe having outlet ports for gas 10 communicating with the passages between the pipes.

3. A device of the class described comprising a single fitting, pipes depending therefrom and spaced one within the other, the innermost pipe being a discharge pipe, fastening means at the 15 upper end of the inner pipe preventing removal thereof downwardly from the fitting, the outermost pipe terminating below the upper end of the 20 innermost pipe and providing passages between the same and the other pipe for the inlet of gas, a thimble extending into and supporting the outermost pipe at the lower end and into which the innermost pipe is screw-threaded, and 25 said thimble having inlet passages communicating with the interior of the innermost pipe, the outermost pipe having outlet portions for gas 30 communicating with the passages between the pipes, valve-controlled outlet means on the fitting coacting with the discharge end of the innermost pipe, said fitting having a chamber communicating with said passages between the pipes, and an inlet valve structure for the last mentioned chamber.
